Primary Examiner — John R Yeh

CLAIM

The ornamental design for a vehicle cleaning apparatus, as shown and described.

DESCRIPTION

FIG. 1 is a front plan view of the vehicle cleaning apparatus according to my design;

FIG. 2 is a rear plan view thereof;

FIG. 3 is a right side elevation view thereof;

FIG. 4 is a left side elevation view thereof;

FIG. 5 is a top plan view thereof; and,

FIG. 6 is a bottom plan view thereof.
